DESIGN FOR A SLIP OR SIMILAR ARTICLE OF WEARING APPAREL

Amanda Nelson, Kalispell, Mont.

Application January 14, 1942, Serial No. 105,205

Term of patent 7 years

To all whom it may concern:

Be it known that I, Amanda Nelson, a citizen of the United States of America, residing at Kalispell, county of Flathead, and State of Montana, have invented a new, original, and ornamental Design for a Slip or Similar Article of Wearing Apparel, of which the following is a specification, reference being had to the accompanying drawing, forming a part thereof, wherein—

I claim:

The ornamental design for a slip or similar article of wearing apparel, as shown.

AMANDA NELSON.
